UNITED STATES PATENT OFFICE.

WILLIAM E. WINE, OF TOLEDO, OHIO.

HOPPER-DOOR LOCK.

Application filed December 18, 1924. Serial No. 756,721.

The invention relates to securing devices or locks for dump doors of railway cars and has particular reference to a lock for use in connection with doors of that type which 5 are pivoted or hinged at opposite sides of the center line of the car so as to be movable to closed position transversely of the longitudinal axis of the car.

The primary object of the invention, generally stated, is to provide a securing means or locking device for use in connection with this type of dump door so constructed and arranged that the door will be held at more than one point and consequently adequately 15 braced or reinforced to prevent sagging under heavy load conditions.

An important object of the invention is to provide a construction involving attachment or adjuncts which will facilitate forcing 20 the door into closed and seat engaging position by the employment of a suitable pry-bar, one of the elements of such including a portion of the door which may advantageously consist of means acting to stiffen and 25 brace the free end of the door.

Another object of the invention is to provide a construction of the above mentioned character in which the side of the car is formed with an opening located preferably 30 between the door hook assemblies for the insertion of a pry-bar whereby the edge of the opening will serve as a fulcrum when the pry-bar is engaged with a portion of the door such as a reinforcing element 35 mounted at the free end of the door.

A further object of the invention is to provide a door locking mechanism in which the parts may be applied to already existing cars in a simple and easy manner and without necessitating material changes or alterations in the construction of the car or door itself.

The invention further contemplates the provision of various structural details which 45 will result in greatly strengthening the door and associated parts and thereby reduce likelihood of derangement, breakage or damage under any circumstances which may be reasonably expected to arise, the provision 50 of the fulcrum hole and pry receiving or bearing element making it far more easy and convenient to effect full closing of the door than is possible in the ordinary construction.

To the attainment of the foregoing objects and advantages, the invention prefer-

ably consists in the construction, arrangement and combination of parts to be herein-after more fully described and pointed out in the appended claims.

In the drawings, wherein like reference characters designate corresponding parts throughout the several views:

Figure 1 is a horizontal section through a portion of a railway car of the type mentioned, looking toward the bottom thereof and illustrating the door in its normal or closed position.

Figure 2 is a fragmentary side elevation of the car showing the door hooks in co-operative engagement with the door arms for holding the door in closed position.

Figure 3 is a sectional view taken on the line 3—3 of Figure 2, showing the door in closed position and clearly illustrating the 75 fulcrum hole in the side of the car and the reinforcing element carried by the free end of the door forming a convenient pry-bar receiving means.

Figure 4 is a detail end elevation of the 80 reinforcing element.

Figure 5 is a detail elevation thereof looking at the front or outer side.

Referring to the drawings in detail, I have shown a fragment or portion of a car of all-steel construction, only a portion of one-half or one side of the car being disclosed inasmuch as such is entirely sufficient for the purpose of illustrating the invention. A car includes center sills 1, side sills 2, both of 85 the usual channel construction and a floor 3 which is riveted to the upper horizontal flanges of the center and side sills as indicated at 4, the side and center sills thus depending below the general level of the floor. 95

The side of the car is formed of the usual plates or sheets 5 riveted to the outer faces of the side sills 2 and reinforced or stiffened by the vertically extending stakes 7 riveted to the side sheets and side sills, as indicated 100 at 8. The floor 3 is formed with an opening 9 for the discharge of the car lading, and this opening is normally closed by a door 10 arranged beneath the floor and of such size as to overlap the edges of the opening. The 105 floor is preferably stiffened by angle bars 9^a at the sides of the opening 9. The car underframe construction may further include transverse bars or beams 11 extending between and secured to the center and side sills 110 1 and 2, as by means of angle plates 12 and 13, respectively. Extending longitudinally

of the car outwardly of the center sills 1 are channel beams 14 located between the successive transverse bars or beams 11 and secured thereto as by means of angle plates 15.

5 The floor or floor sheet 3 is also riveted to the horizontal flange of the beam 14, as shown at 16.

The mounting for the door 10 includes a pair of hinge brackets 17 riveted or otherwise secured to the outer face of the beam 14 and having pintle pins 18 extending therethrough. Suitably secured, as by rivets shown at 19, to the underside of the door 10 is a pair of door arms 20 formed as angle bars. The inner ends of the door arms, that is, the ends remote from the side of the car, are shown as coped to define elongated strips 21 formed into knuckles 22 engaged within the brackets 17 and pivoted with respect thereto by means of the pintles 18 above described. Obviously, the door arms could be mounted irrespective of the hinge connections though the above mentioned construction is obviously preferable inasmuch as it reduces the number of parts and provides a strong and rigid connection which will insure proper movement of the door when swung into open or closed position, as the case may be. The outer ends of the door arms are of angular formation or shape and include downwardly and outwardly inclined portions 23 terminating in horizontal outward extensions 24 which extend beneath and project beyond the side of the car, as clearly indicated. As stated above, the door arms are conveniently formed of angle bars and these bars are preferably arranged with their horizontal flanges extending toward each other, as indicated in Figure 2 for cooperation with means to be described.

One of the features of the invention is the provision of a reinforcing and bracing bridge member 25 which is located beneath the free end portion of the door 10 and secured thereto as for instance by means of the rivets 26. This member 25 is substantially Z-shaped and includes the horizontal flange engaging against the underside of the door and further includes an angularly deflected edge portion 27 conformingly engaging against the inclined portions 23 of the door arms 20 and secured thereto as for instance by the rivets 28. Owing to the fact that this member 25 bridges the space between the downwardly inclined portions of the door arms and the door, it is quite obvious that it will exert a very efficient bracing action and make the door structure rigid and strong so that all the strain will not come upon the rivets or other securing devices 19.

For holding the door in closed position, I provide a pair of lock assemblies designated broadly by the numeral 29 arranged in reversed or opposed relation and mounted

upon the outside of the car side 5. Each of these assemblies includes a suitable bracket 30 within which is pivoted, as at 31, a hook 32 having ledges 33 and 33^a adapted to be engaged beneath the outer projecting end of a door arm 20. Each assembly further includes a locking cam 34 pivoted within the bracket 30 and engageable with the hook 32 for the purpose of holding the latter firmly in engagement with the associated door arm and preventing unintentional displacement.

In doors of this character it is highly desirable that some provision be made whereby the door may be pried into its final closed position by means of a pry-bar, crow-bar or the like. As a consequence, I provide an opening 35 in the side sheet 5 of the car and a registering hole 36 in the adjacent side sill 2. An opening 37 may also advantageously be provided in the reinforcing member 25 preferably in alinement with the openings 35, 36, so that all of said openings are midway between the door hook assemblies and of course midway between the door arms 20.

In the use of a door constructed in accordance with this invention, it is obvious that when the hooks 32 are disengaged from the extensions 24 of the door arms the door will swing open and it is the ordinary practice for the builder to provide a stop, not shown, for the purpose of limiting the opening movement. Assuming that the car lading has been discharged subsequent to opening of the door, when it is desired to close and lock the door it may be swung by hand upwardly until the extensions 24 of the door arms engage with the first ledges 33^a on the hooks 32. This auxiliary locking ledge on the hooks provides means whereby the door or doors, although distorted by service, may be easily held in temporary locked position. After this is done, a suitable pry-bar, crow-bar or other similar tool may be inserted through the holes 35, 36 and 37 and the bar then pulled downwardly so that the lower edges of the holes 35 and 36 will serve as a fulcrum. This downward movement of the outer end of the pry-bar will naturally result in forcing the door 10 upwardly to its seat against the underside of the floor 3, whereupon the hooks 32 will swing or be so moved that the ledges 33 thereof may be engaged beneath the extensions 24 of the door arms and the cams 34 swung into engagement with the hooks for holding them against possible displacement.

It will be readily appreciated that the fulcrum feature of the invention is not limited in its application to doors of any particular construction as the elevation of the opening formed in the side of the car may be varied so as to enable the inner end of the prying tool to engage with any desired portion of the door. Furthermore, as it has

been found that the door, notwithstanding that it has become warped, can often, without great difficulty, be raised to a position such that the main ledge 33 of one of the 5 pair of hooks can engage its door arm, it will be perceived that in such cases the auxiliary ledge 33a is not called upon to aid in the closing of the door. When the main ledge 33 of one of the hooks engages with 10 its door arm in the manner just described, it is obvious that the pry-bar may be used to forcibly move the door to permit the other of the hooks to supportingly engage its associated door arm.

15 A hopper door provided with the door arms and reinforcing plate or bridge member, as described and provided with the pair of hook devices, will be not only strong and durable in service but also extremely easy 20 and convenient to operate, owing to the provision of the means facilitating prying of the door to its seat so that full closure thereof is easily effected.

While I have shown and described the 25 preferred embodiment of the invention, it is of course to be understood that various changes in the details of construction and the arrangement of parts may be resorted to in order to widen the field of utility, provided, however, that such variations and 30 modifications constitute no departure from the spirit of the invention or the scope of the claims hereunto appended.

Having now described my invention, what 35 I claim and desire to secure by Letters Patent, is:

1. In a railway car having a side sheet, a discharge opening in the floor of the car, a hingedly mounted door for closing said 40 opening, a door arm secured to said door, means engageable with the door arm for supporting the door in closed position, and fulcrum means located in the side sheet of the car adapted to receive a pry-bar for forcing the door to closed position.

2. In a railway car having a discharge opening, a hingedly mounted door for closing the opening, a pair of door arms secured to the underside of the door in spaced relation and projecting beyond the side of the car, a pair of hook assemblies mounted on the outside of the car in spaced relation and each including a bracket, a hook pivoted therein and having ledges adapted to be engaged beneath the door arm and further including a locking cam engageable with the hook for holding the same against disengagement from the door arm, and fulcrum means located in the side of the car between

55 said hook assemblies adapted to receive a pry-bar engageable with the free end of the door whereby the door may be pushed up to its seat.

3. In a railway car having a discharge 60 opening, a hingedly mounted door for clos-

ing the opening, a pair of door arms secured to the underside of the door in spaced relation and projecting beyond the side of the car, a pair of hook assemblies mounted on the outside of the car in spaced relation 70 and each including a bracket, a hook pivoted therein and having ledges adapted to be engaged beneath the door arm and further including a locking cam engageable with the hook for holding the same against disengagement from the door arm, the side of the car being provided with a hole located between the planes of the door and of the hook engaging portions of the door arms adapted to receive a pry bar and to serve 80 as a fulcrum therefor whereby the pry bar may be engaged with the free end of the door for forcing the same upwardly to its seat.

4. In a railway car having a discharge 85 opening, a hinged door for closing the opening, a pair of door arms secured to the underside of the door and projecting beyond the side of the car, holding means for the door arms including a pair of hook assemblies 90 mounted on the outside of the car and each including a bracket, a hook pivoted therein for engagement with the door arm and a locking cam for engagement with the hook, the side of the car being formed with 95 a hole located between the hook assemblies adapted to receive a pry-bar, and a reinforcing member secured to the underside of the free end of the door and having a hole adapted to receive the pry-bar. 100

5. In a railway car having a discharge opening, a hingedly mounted door for closing the opening, a pair of door arms secured to the door and projecting beyond the side of the car, pivoted hooks engageable with the door arms, reinforcing member secured beneath the free end of the door and secured to the door arms, the side of the car being provided with a hole located between the hooks thereon and adapted to receive a pry-bar, and said reinforcing member having a corresponding hole adapted to receive the pry-bar, the first named hole providing fulcrum means for the pry-bar. 110

6. A railway car having a discharge opening, a hingedly mounted door for closing said opening, a door arm secured to the door, means engageable with the door arm for supporting the door in closed position, the side of the car being formed with fulcrum means 115 adapted to receive a pry-bar, and a reinforcing member secured to the underside of the door at an oblique angle to the door arm and having an aperture for receiving the pry-bar. 120

7. A railway car having a discharge opening, a hingedly mounted door for closing said opening, a door arm secured to the door, means engageable with the door arm for supporting the door in closed position, and 125

a reinforcing member secured to the door, the side of the car being provided with a hole adapted to receive a pry-bar, and said reinforcing member having a corresponding hole for receiving the pry-bar.

8. In a railway car having its bottom provided with a discharge opening, a hingedly mounted door for closing the opening, door arms secured to the underside of the door and including downwardly and outwardly inclined portions terminating in extensions projecting beyond the side of the car, securing means mounted on the outside of the car engageable with said extensions, and a reinforcing member of substantially Z-shape secured to the underside of the free end of the door and secured to the inclined portions of the door arms.

9. In a railway car having its bottom provided with a discharge opening, a hingedly mounted door for closing the opening, door arms secured to the underside of the door and including downwardly and outwardly inclined portions terminating in extensions projecting beyond the side of the car, securing means mounted on the outside of the car engageable with said extensions, and a reinforcing member of angular formation secured to the underside of the free end of the door and secured to the inclined portions of the door arms, the side of the car being formed with a hole located between the retaining members, and said reinforcing member being formed with a hole, said holes being provided for the passage of a pry-bar for forcing the door into closed position, the first named holes serving as fulcrum means for the pry-bar.

10. A railway car having an underframe construction involving a center sill and a

side sill, a floor for said car having a discharge opening, a hinged door for closing said opening having its hinge axis substantially parallel to the center sill, a door arm secured to the door, and means for holding said door in closed position, the side sill being apertured to receive a pry-bar for forcing the door to closed position.

11. A railway car having a floor provided with a lading discharge opening and a side sill depending below the general level of the floor, a gravity actuated door for closing said opening, and means for supporting the door in closed position involving pivoted means carried by the car body and an arm secured to the door, the outer end of said arm being spaced from the door and projecting outwardly beyond the side sill for cooperating with said last named means, the side sill being provided intermediate its upper and lower edge with a fulcrum to cooperate with a pry-bar for forcing the door to closed position.

12. A railway car having a floor provided with a lading discharge opening and a side sill depending below the general level of the floor, a gravity actuated door for closing said opening, and means for supporting the door in closed position involving a pivoted hook carried by the car body and an arm carried by the door, the said arm passing beneath and projecting outwardly beyond the said sill for cooperating with the said hook, the sill being apertured to receive a pry-bar for forcing the door to closed position.

In testimony whereof I affix my signature.

WILLIAM E. WINE.
